UNITED STATES PATENT OFFICE.

EDWARD S. SAVAGE, OF ROCHESTER, NEW YORK.

DRIVING MEANS FOR TOY VEHICLES OR THE LIKE.

Application filed June 6, 1923. Serial No. 643,804.

The present invention relates to driving means for toy vehicles or the like, an object of this invention being to provide a construction in which a speed increasing gearing is employed in such a manner that upon the winding of the spring through the propelling wheel, said gearing is effective. Another object of the invention is to provide a construction which is of compact form so that it may be readily housed in a wheel and an axle of the toy. Still another object of the invention is to provide an improved means of interposing a speed increasing mechanism or gearing between a propelling wheel of a vehicle and a motor driven member.

To these and other ends, the invention consists of certain parts and combinations of parts, all of which will be hereinafter described, the novel features being pointed out in the appended claims.

In the drawings:

Fig. 1 is a side view of a toy constructed in accordance with this invention;

Fig. 2 is a longitudinal section through the rear wheels and an axle of the toy vehicle;

Fig. 3 is a section on the line 3—3, Fig. 2;

Fig. 4 is a section on the line 4—4, Fig. 2;

Fig. 5 is a section on the line 5—5, Fig. 2;

Fig. 6 is a section on the line 6—6, Fig. 2; and

Fig. 7 is a fragmentary sectional view of another embodiment of the invention;

Referring to the embodiment of the invention illustrated in Figs. 1 to 6, 1 indicates a figure toy vehicle such as a bear, which has a front axle 2 on which wheels 3 turn. A rear axle 4 connects the rear legs and is, in this instance, in the form of a stationary tube held against turning on the legs. In this tube is mounted a helical spring 5 which at one end 6 is secured to the tubular axle, the other end being secured to a spring rotated or motor driven member 7 also in the form of a tube, spaced from the tube 4 to provide a chamber for the spring 5, the spring being secured at 8 to this inner tube or spring rotating member. Extending through the tube 7 is a shaft 9 which has two wheels 10 and 11 rigidly secured to opposite ends thereof. In this instance, an internal cup shaped hub 12 is provided on the wheel 11 and the shaft 9 is formed with a non-circular portion 13 extending through this hub and the outer wall of the wheel, the wheel being confined between the upset por-

tion 14 on the outer end of the non-circular portion and a shoulder 15 at the inner end of the non-circular portion. A disk 16 is secured to the tube 4 and forms a closure for the inner face of the wheel 11, its edge being turned inwardly at 17 to provide a flange. The wheel 10 is hollow or cup shaped and has a sleeve 18 rigidly secured thereto and also rigidly secured to the shaft 9, so that the two wheels 10 and 11 turn together.

A speed increasing gearing is interposed between the spring rotated member 7 and the hollow winding and propelling wheel 10. This speed increasing gearing, in this instance, embodies a flange 19 secured to the spring rotated member or sleeve 7 within the wheel 10 and having a stub shaft 20 supported thereon. This stub shaft acts to support a pinion 21 which meshes with a gear 22 formed on the sleeve 18. The pinion 21 meshes also with an annular internal gear 23 and is supported by a ring 24, the latter being journaled between two flanges 25 and 26 secured to the stationary sleeve 4 adjacent the wheel 10. The ring 24 is adapted to turn in one direction relatively to the stationary sleeve or tube 4, while in the other direction it is held against turning relatively to the sleeve. This latter result is effected, in this instance, by providing a ring 24 with a pawl 27 pivoted at 28 to the ring 24 and held by a spring 29 toward the lateral teeth or projections 30 formed on the flange 26. The pawl 27 acts in such a direction that when the spring 5 turns the spring rotated member 7, the gear 21 will be revolved about the axis of the winding and propelling wheel 10 and will also rotate on the stub shaft 20, thereby causing the gear 22 to be rotated to rotate the wheel 10, axle 9 and the wheel 11 in the direction to propel the toy.

The winding of the spring is effected by directly connecting the wheels 10 and 11 with the spring rotated member. This is effected, in this instance, by providing teeth or projections 31 on the flange 19 of the spring rotated member and providing centrifugally operated detents 32 on the inner face of the wheel 10, these detents being pivoted at 33 and having noses 34^a arranged to cooperate with the projections 31. The detents are so weighted that, with the rotation of the wheel, the weighted portions are thrown outwardly and the noses 34 are thrown inwardly so that one of them will engage with the projection 31 as shown in

Fig. 3, thus establishing a direct connection between the wheel 10 and the spring rotated member 7. It is apparent that when the wheel rotates in the direction for propelling the toy, these detents ride over the projections without making any connection therewith. When the detents engage the projections, the axis 20 of the gear 21 will revolve and the gear 22 rotates about such axis 20 at the time of such revolution. The toothed connection between the gear 21 and the internal gear 30 causes the latter to rotate on the tubular stationary axle 4 on the winding of the spring, this being permitted by the pawl 27 riding over the teeth 30, so that the speed increasing gearing is ineffective, when a direct connection is established between the winding and propelling wheel and the spring rotated member.

A governor for the motor is preferably mounted in the hollow wheel 11 and to this end comprises a centrifugal governor consisting of two weighted members 34 and 35, the former being pivoted at 36 and the latter at 37 to the inner face of the hollow wheel 11. A link 38 is pivoted at 39 to the weighted member 34 and at 40 to the weighted member 35, and a leaf spring 41 secured at 42 to the wheel 11 acts on the weighted member 35 to oppose the outward movement of the members. The lug 43 extending laterally from the weighted member 34 is adapted to cooperate with the flange 17 on the disk 16 secured to the stationary hollow axle tube 4. With this arrangement, when the speed of the toy increases the weighted members 34 and 35 are swung outwardly at their free ends against the action of the spring 41, thus tending to retard the motion of the toy. This is further retarded by the frictional engagement of the spring 41 and the flange 17 of the disk 16.

Each wheel may have a depressed portion 44 in its periphery and in this depressed portion a rubber tire 45 may be secured.

In the embodiment of the invention shown in Fig. 7 the governor is dispensed with and the spring 5^a is arranged in the wheel 11^a corresponding with the wheel 11 in the embodiment shown in Figs. 1 to 6. The spring, in this instance, is of flat volute form having one end secured to the flange 17^a on the disk 16^a rigidly secured to the tubular stationary shaft 4. The other end of the spring 5^a is secured to the spring rotated member 7^a. The shaft 9^a is journaled in the spring rotated member 7^a and is connected to the wheel 11^a. The other parts in this construction are substantially the same as those illustrated in Figs. 1 to 6.

In order to wind the spring of the motor, the toy is moved back and forth on a suitable surface. When moving backwards the spring is wound, due to the fact that the

detents 32 engage the projection 31 and form a direct connection with the spring rotated member 7, the gear 21 causing the annular gear 23 to turn on the stationary tubular axle 4 and rendering the speed increasing gearing ineffective. When the toy is released, the spring turns the spring rotated member 7 and revolves the gear 21 which, owing to its meshing with the annular gear 23, the latter being held against turning by the pawl 27, turns the gear 22 and rotates both wheels 10 and 11. The speed of rotation of the wheels is controlled, by the centrifugal governor mounted in the wheel 11.

What I claim as my invention and desire to secure by Letters Patent is:

1. Driving means for toy vehicles comprising a stationary part, a motor driven part, a spring interposed between the stationary part and the motor driven part, an internal gear, means connecting such internal gear to the stationary part to permit it to move relatively thereto in one direction, while holding it against turning relatively to the stationary part in the other direction, a driving wheel, a pinion on the wheel, means connecting said driving wheel with the motor driven part to permit the wheel to turn relatively to the motor driven part in one direction, while causing the wheel to connect with the motor driven part to move such part when the wheel is turned in the other direction, and a pinion mounted to turn on the motor driven part about an axis eccentric to the axis of turning of the wheel, meshing with the pinion on the wheel and also with the internal gear.

2. Driving means for toy vehicles comprising a stationary part, a rotary motor driven member, a gear rotatable about its axis and having its axis revolvable about the axis of turning of the rotary motor driven member, a wheel turning about the axis of turning of the rotary motor driven member, a pinion concentric with the axis of turning of the wheel and meshing with the rotary gear, means for connecting the wheel directly with the motor driven member when the wheel is held against turning relatively to the stationary part in one direction and means connected with the stationary part for imparting a turning movement to said rotary gear as the latter revolves, said means being ineffective when the wheel is directly connected to the rotary motor driven member.

3. Driving means for toy vehicles comprising a stationary part a rotary motor driven member, a wheel turning about the axis of turning of the rotary motor driven member, means for connecting the wheel to the rotary driven member when the wheel is turned in one direction, a pinion turning with the wheel and having its axis coincident with

the axis of turning of the wheel, a rotary gear meshing with the pinion and carried by the rotary motor driven member at a point eccentric to the axis of turning of such rotary motor driven member, a gear on the stationary part to cause the turning of the rotary gear as the latter is revolved, and means for preventing the turning of such rotary gear when the latter is revolved and 10 the wheel is directly connected to the rotary motor driven part.

4. The combination with a motor driven member, and a hollow propelling wheel, of speed increasing mechanism between the motor driven member and the hollow propelling wheel embodying a gear within the hollow propelling wheel, a pinion mounted within the hollow propelling wheel on the motor driven member and revolving with 15 said member about the axis of turning of the hollow propelling wheel, said pinion meshing with the gear on the hollow propelling wheel, and a gear mounted on a fixed part and meshing with the pinion as the latter is revolved by the motor driven member.

5. The combination with a tubular stationary axle, a tubular motor driven member arranged in said axle, a spring connected with said tubular stationary member, a shaft 20 extending through said tubular motor driven member, wheels connected to opposite ends of the shaft, one of said wheels being hollow, a gear arranged within said hollow wheel, a pinion connected to the motor driven member within the hollow wheel meshing with the gear and revolvable with the motor driven member about the axis of turning of the shaft, and an internal gear supported by said hollow stationary axle 25 and meshing with said pinion.

6. A driving mechanism for toy vehicles comprising a tubular stationary axle, a tubular spring rotated member extending through said axle, a spring connected with 30 said tubular stationary member, a shaft extending through said tubular spring rotated member, wheels connected to opposite ends of the shaft, one of said wheels being hollow, a gear arranged within said hollow wheel, a pinion connected to the spring rotated member within the hollow wheel meshing with the gear and revolvable with the spring rotated member about the axis of turning of the shaft, an internal gear supported by 35 said hollow stationary axle and meshing with said pinion, said internal gear being rotatable in one direction independently of the hollow stationary axle, and means for connecting the hollow wheel with the spring rotated member to rotate the latter directly for winding the spring.

7. A driving mechanism for toy vehicles comprising a tubular stationary axle, a tubular spring rotated member extending 40 through said axle, a spring connected with

said tubular stationary member, a shaft extending through said tubular spring rotated member, wheels connected to opposite ends of the shaft, one of said wheels being hollow, a gear arranged within said hollow wheel, 45 a pinion connected to the spring rotated member within the hollow wheel meshing with the gear and revolvable with the spring rotated member about the axis of turning of the shaft, an internal gear supported by 50 said hollow stationary axle and meshing with said pinion, said internal gear being rotatable in one direction independently of the hollow stationary axle, and means for connecting the hollow wheel with the spring rotated member to rotate the latter directly for winding the spring, said means comprising a pawl on the hollow wheel and projecting on the spring rotated member.

8. The combination with a hollow stationary axle, a tubular spring rotating member mounted in said axle, a spring connected with said tubular spring rotated member to turn the same in one direction, a shaft 55 extending through said spring rotated member and turning therein, wheels connected to opposite ends of said shaft, a speed increasing means between the tubular spring rotating means and the shaft, and means for directly connecting the shaft with the tubular spring rotated member when the shaft is directly connected with the tubular spring rotated member.

9. A driving mechanism for toy vehicles or the like, comprising a stationary tubular axle, a tubular spring rotated member movable in the axle, a shaft turning in the tubular spring rotated member, a spring connected to the stationary axle and to the spring rotated member, two wheels connected to the axle, one of said wheels being hollow, a gear arranged in said hollow wheel, a flange secured to the spring rotated member within the hollow wheel and having 60 projections thereon, a pinion mounted on said flange to be revolved by the spring rotated member and meshing with the gear in the hollow wheel, a dog mounted in the hollow wheel and cooperating with the projections in the flange to provide a direct connection between the hollow wheel and the spring rotated member, an internal gear meshing with the pinion and mounted to turn on the stationary hollow axle, and means for holding said internal gear against 65 turning in one direction so that said internal gear may be employed for turning the pinion as the latter is revolved by the spring rotated member and thereby turning the two wheels at an increased speed.

10. A driving mechanism for toy vehicles or the like comprising a motor spring, a spring rotated member, a hollow propelling wheel, and speed increasing mechanism between the spring rotated member and the

propelling wheel mounted in the hollow propelling wheel.

11. A driving mechanism for toy vehicles or the like comprising a tubular motor driven member, a shaft extending through said member, wheels connected to opposite ends of the shaft, one of said wheels being hollow, and a governor for the motor mounted in said hollow wheel.

12. A driving mechanism for toy vehicles or the like comprising a tubular motor driven member, a shaft extending through said member, wheels connected to opposite ends of the shaft, one of said wheels being hollow, and a governor for the motor mounted in said hollow wheel, said governor comprising centrifugally operated members movable outwardly with reference to the shaft under centrifugal force and spring means opposing said outward movement.

13. The combination with a hollow axle, a tubular motor driven member mounted in said axle, a helical spring arranged about the tubular motor driven member within the hollow axle and having one end secured

to the axle and the other end secured to the tubular motor driven member, a shaft extending through the tubular motor driven member and turning therein, wheels on the shaft and speed increasing means connecting said tubular motor driven member with the wheel and arranged beyond the hollow stationary axle and the tubular motor driven member.

14. A driving mechanism for toy vehicles or the like comprising a rotary member, suitable driving means for rotating said member, a rotary gear, means supporting said gear so that the axis of the gear revolves about the axis of the rotary member, means cooperating with the rotary gear during its revolution about the axis of the rotary member for rotating said gear, and a supporting and driving wheel for a toy or the like driven by the rotation of the gear while the axis of the latter is revolving about the axis of rotation of the rotary member.

EDWARD S. SAVAGE.
